UNITED STATES PATENT OFFICE.

WALTER M. GLEESON, OF FOND DU LAC, WISCONSIN.

RAIL-JOINT.

1,088,562.

Specification of Letters Patent. Patented Feb. 24, 1914.

Application filed May 16, 1913. Serial No. 788,150.

To all whom it may concern:

Be it known that I, WALTER M. GLEESON, a citizen of the United States, residing at Fond du Lac, in the county of Fond du Lac and State of Wisconsin, have invented new and useful Improvements in Rail-Joints, of which the following is a specification.

The present invention relates to improvements in a combined rail joint and chair for 10 railway rails, and has for its object the provision of means whereby the rails will be secured together at their meeting ends in a manner which will provide a smooth joint, whereby the wheels will be prevented from 15 pounding the ends of the rails.

With the above recited object in view, and others which will appear as the nature of the invention is more fully understood, the improvement resides in the construction, 20 combination and arrangement of parts set forth in the following specification and falling within the scope of the appended claims.

In the drawing: Figure 1 is a perspective view of my rail joint and chair as applied to the meeting ends of two rails, Fig. 2 is a plan view of the combined rail joint and chair, Fig. 3 is a transverse sectional view on the line 3—3 of Fig. 1, showing the arrangement of the base plates of the combined joint and chair before a spike has been inserted in the central rail supporting tie, and Fig. 4 is a similar sectional view after the spike has been driven home.

Referring to the drawings in detail, R—R designate two rails which are adapted to be supported upon and connected by my improved rail joint and chair, and T the ties for the rails and chairs. One of these ties is 40 arranged directly below and centrally of the meeting ends of the rails, while the remaining ties are disposed at a desired distance from the central tie.

My improvement includes two members each provided with a substantially rectangular base 1 which is horizontally straight, and which preferably has its lower face provided with longitudinally extending ribs or teeth 2. The base members 1 are adapted 50 to be arranged upon the tie T and to receive thereon the rails R. The base members 1 have their inner longitudinal edges spaced a slight distance from the central portions of the base flanges of the rails R, and their 60 outer longitudinal edges project a suitable distance beyond the outer longitudinal edges

of the base flanges of the said rails. These longitudinal edges of the base members 1 are provided, at their portions which rest upon the ties T with apertures 3, the inner 60 walls 4 of which being inclined toward the inner longitudinal edges and the aperture are adapted to receive securing spikes 5 which force the ribs or teeth 2 into the ties T and so obviate the lateral movement of 65 the said base members, as well as preventing the longitudinal movement of the said members. Each of the base members 1 is integrally formed upon its outer longitudinal edge with centrally arranged angle plates 6, 70 the said plates adapted to have their horizontal portions 7 contact with the upper faces of the flanges of the rails and their vertical portions 8 contact with the webs of the rails and the upper longitudinal edges 75 of said vertical portions engage beneath the heads of the rails. The angular plates 6 are formed of resilient material, and when arranged upon the rails and before the spikes are inserted, the said angular plates 80 contact with the rails, while the base portions 1 are sustained at a slight angle to the base flanges of the rails.

By reference to Figs. 3 and 4 of the drawings, it will be noted that the apertures 3 85 have their inner walls 4 inclined from the upper corners of the outer longitudinal edges of the plates, so that the spikes 5 when inserted in the ties will force the base portions 1 to a horizontally straight position 90 and in tight engagement with the underfaces of the base flanges of the rails, as well as having a tendency to force the angular plates into contact with the flanges and webs of the rails, and particularly force the 95 upper longitudinal edges of the vertical longitudinally disposed portions 8 tightly beneath the heads of the rails. The vertical portions 8 of the angular plates are provided with openings which register with 100 similar openings in the webs of the rails, and the registering openings are adapted for the reception of the usual bolts which are provided with the usual nuts.

The plates 6 it will be noted, are arranged 105 medially of the base members 1 and of course have their ends terminating a suitable and desired distance from the ends of the said base members, and from the above description, taken in connection with the accompanying drawing, the simplicity of the 110 device as well as the advantages thereof

will, it is thought, be perfectly apparent to those skilled in the art to which such inventions appertain without further detailed description.

Having thus described the invention, what I claim as new is:

1. The combination with two rail ends and ties for the rails, one of said ties being disposed directly below the ends of the rails, of a combined rail joint and chair, said rail joint and chair including a pair of members each having a horizontally straight base member which rests upon the ties and which receives the rails, each of the plates having its outer longitudinal edge centrally provided with an elongated angular plate, each of said plates being shaped to conform with the fishing spaces of the rail end to centrally contact with the rails and to normally force the base members out of contact with the base flanges of the rail, the said outer longitudinal edges of the base members and the plates therefor being provided with apertures which have their inner walls inclined from the upper corners of the base members inwardly therefrom, spikes adapted to be guided by the inner wall of the apertures into the tie and to spring the base flanges into tight direct contact with the base portions of the rails without interfering with the contact of the angular plates with the rails; and means for securing the angular plates to the webs of the rails.
2. The combination with two rail ends

and ties for the rails, one of said ties being disposed directly below the ends of the rails, of a combined rail joint and chair, said rail joint and chair including a pair of members each having a horizontally straight base member which rests upon the ties and which receives the rails, the lower faces of base members being provided with longitudinal ribs, each of the plates having its outer longitudinal edge centrally provided with an elongated angular plate, each of said plates being shaped to conform with the fishing spaces of the rail and to normally hold the base members out of direct contact with the base flanges of the rail, the said outer longitudinal edges of the base members and plates therefor being provided with apertures which have their inner walls inclined from the upper corners of the base members inwardly therefrom, spikes adapted to be guided by the inner wall of the apertures into the tie and to spring the base flanges into direct contact with the base portions of the rails and to embed their ribs within the tie, without interfering with the contact of the angular plates with the rails, and means for securing the angular plates to the webs of the rail.

In testimony whereof I affix my signature in presence of two witnesses.

WALTER M. GLEESON.
